RUG POLE

Karl E. Hebenstreit, Los Angeles, Calif.

Application March 18, 1948, Serial No. 15,670

4 Claims. (Cl. 211—117)

1

This invention relates to supporting structures and particularly pertains to a rug pole.

When rugs and similar articles are to be displayed or are to be cleaned and dried it is desirable to suspend the rug from a horizontally extending support along which the upper edge of the rug may be easily secured to and removed from the support. It is also desirable to construct a supporting device which may be disposed horizontally and which is of sufficient strength to prevent sagging of the support and of light weight so that when it is necessary to elevate and lower the support this may be accomplished by a minimum amount of effort.

It is the principal object of the present invention therefore to provide a supporting device which is light in weight and which may be easily constructed to provide a horizontal member which will engage the upper edge of the rug or the like and support the same without sagging.

The present invention contemplates the provision of a rug pole made of a tubular, metal structural element, the cross-section design of which insures great strength, the structure further being equipped with simple means for engaging the rug and supporting the same.

The invention is illustrated by way of example in the accompanying drawings in which:

Figure 1 is a view in side elevation indicating the assembled rug pole with a rug suspended therefrom.

Fig. 2 is an enlarged fragmentary view in side elevation showing details of construction of the rug pole and the hanging saddle by which it is carried.

Fig. 3 is a view in transverse section through the rug pole as seen on the line 3—3 of Fig. 2 and shows the section of the tubular metal pole and one of the pole pins.

Fig. 4 is a view in end elevation showing a modified form of the invention including a conventional square-sectioned tubular pole and a wooden strip at the top thereof.

Referring more particularly to the drawings, 10 indicates a rug pole of the character with which the present invention is concerned. This pole is fitted with hanging saddles 12 and 13 adjacent its opposite ends, to which supporting cords or cables 14 or 15, respectively, may be attached. These cables may be led over pulleys 16, 17 and 18, so that a rug 19 may be lifted to a vertically suspended position when attached to the rug pole 10. In the preferred form of the invention the rug pole is of the sectional shape shown in Fig. 3 of the drawings. Here it will be seen that the

2

transverse section of the pole is substantially rectangular as defined by a horizontal bottom wall 20, parallel spaced side walls 21, and upwardly and inwardly extending side wall continuing portions 21'. The upper end of the continuing portions 21' are formed integral with the transverse horizontal portion 22. The wall portions 20, 21 and 21' are relatively thin and are of uniform thickness. The upper wall portion 10 22 is materially greater in thickness and thus provides suitable metal through which threaded bores 23 are formed. These threaded bores are spaced at intervals throughout the length of the pole and when the pole is suspended their axes extend 15 vertically. The threaded bores are designed to receive the threaded shanks 24 of pointed pole pins 25. The pole pins extend along the central vertical axis of the member 24 and project upwardly above the upper face of the portion 20 22 of the rug pole. The pins are provided to pierce the fabric of the rug 19 or other article 26 to be supported and have sufficient collective strength throughout the length of the rug pole to support the article 19. In view of the fact that 25 the rug or the like may be suspended for drying it will have considerable weight and it would dry with a very hard crease in it if the upper edge hung over a square edge on a supporting member. For that reason the upper extensions 30 21' of the side walls of the rug pole incline upwardly and inwardly and allow the rug to hang down naturally over the curved surface 26.

The rug pole is supported at its opposite ends by the hanging saddles 12 and 13. These are 35 secured pivotally to the pole by horizontally extending saddle pins 27 which extend transversely through the pole at its opposite ends. Stop bolts 28 also extend through the pole 10 at points outwardly of the saddle pins 27 and in a horizontal plane above the pins 27 so that the saddles 12 and 13 will swing only a limited distance longitudinally of the pole. The saddles are U-shaped members which straddle the ends of the pole and in the upper looped portions have a hook 29 which 40 will receive one of the cords or cables previously described as being provided to lift the pole and the article fastened thereon.

In Fig. 4 of the drawings a modified form of the invention is shown in which the pole is indicated as comprising a square tubular metal member 39 provided with the saddles 12 and 13 as previously described. Extending longitudinally of the upper face of the tubular element 30 is a hardwood bar 31 which is secured in position by bolts 32. This bar has oppositely in-

clined side portions 33 adjacent its upper horizontal face 34. Extending upwardly from the face 34 and spaced equidistant longitudinally thereof is a plurality of pole pins 25 performing the function previously set forth.

In the operation of either form of the present invention the rug pole is attached to the hanging saddles 12 and 13 and these may be secured to supporting cables which may be hung in any desired manner but which are usually mounted so that they will lift or lower the rug pole. When the rug pole has been lowered the edge of a rug or the like may be attached thereto by causing the series of pole pins to penetrate the rug adjacent to an edge thereof. The pole may then be lifted until the rug is entirely clear of the floor. The weight of the rug will then be imposed entirely on the pole pins 25 and it will be drawn downwardly along an inclined face of one of the side wall extensions 21' after which it will hang over the edge 26 and then extend downwardly along one of the side walls of the tubular section of the pole. In the form of the invention shown in Fig. 4 the operation will be the same.

It will thus be seen that the rug pole here disclosed may be extremely light in weight and at the same time it will have sufficient structural strength to resist any sagging action and to insure that the rug or the like will be supported straight and firm. It will also be evident that by the structure here disclosed it is possible to raise and lower the rug pole easily since it is light in weight.

While I have shown the preferred form of my invention as now known to me, it will be understood that various changes may be made in combination, construction and arrangement of parts by those skilled in the art, without departing from the spirit of my invention as claimed.

Having thus described my invention, what I claim and desire to secure by Letters Patent is:

1. A rug pole or the like comprising a metal pole of tubular section, said section being formed by a lower wall, opposite parallel horizontal wall portions terminating in upwardly and inwardly inclined wall sections connected by an upper horizontal wall section, saddle members attached to opposite ends of said pole for the support of same, a plurality of pole pins spaced longitudinally along the upper wall section of the pole and centrally thereof, said pole pins extending vertically to pierce the fabric of an article to be supported and to allow the fabric to hang downwardly along the upper inclined face of the pole and vertically downwardly along a side wall of the pole, said

55

4
pole pins being formed with a threaded base portion by which the pins may be detachably secured to the upper wall of the pole.

2. A rug pole or the like comprising a metal tubular pole having an upper wall section, a series of threaded openings spaced longitudinally along the upper wall section of the pole, a series of pole pins having threaded base portions threaded into the openings along the upper wall of the pole, and saddles connected to opposite ends of said pole whereby the pole may be supported in a horizontal position.

3. A rug pole or the like comprising a metal tubular pole having an upper wall section, a series of threaded openings spaced longitudinally along the upper wall section of the pole, a series of pole pins having threaded base portions and being adapted to be threaded into the openings along the upper wall of the pole, and saddles at the opposite ends of said pole whereby the pole may be supported in a horizontal position, said saddles being U-shaped in form and having legs which straddle the pole, and pivot bolts passing through said saddle legs and the pole to pivotally secure the saddle to the pole.

4. A rug pole or the like comprising a metal tubular pole having an upper wall section, a series of threaded openings spaced longitudinally along the upper wall section of the pole, a series of pole pins having threaded base portions and being adapted to be threaded into the openings along the upper wall of the pole, saddles at the opposite ends of said pole whereby the pole may be supported in a horizontal position, said saddles being U-shaped in form and having legs which straddle the pole, pivot bolts passing through said saddle legs and the pole to pivotally secure the saddle to the pole, and stop means limiting the outward swinging movement of the saddles.
